C. LOMBARDO,
KNOCKDOWN CRATE,
APPLICATION FILED SEPT. 6, 1918.

1,333,857.

Patented Mar. 16, 1920.

UNITED STATES PATENT OFFICE.

CHARLES LOMBARDO, OF WATERFORD, NEW JERSEY.

KNOCKDOWN CRATE.

1,333,857.

Specification of Letters Patent. Patented Mar. 16, 1920.

Application filed September 6, 1918. Serial No. 252,910.

To all whom it may concern:

Be it known that I, CHARLES LOMBARDO, a citizen of the United States, residing at Waterford, in the county of Camden, State of New Jersey, have invented certain new and useful Improvements in Knockdown Crates; and I do hereby declare the following to be a full, clear, and exact description of the invention, such as will enable others skilled in the art to which it appertains to make and use the same.

The present invention relates to new and useful improvements in folding crates more particularly of that type including a pair of rigid side frames adapted to be held in spaced relation in the assembled condition of the crate by releasable connecting bars.

It is in general the object of the present invention to simplify and otherwise improve the structure and to increase the strength of knockdown structures of this character, particularly when assembled, and to increase the ease of manipulation of devices of this character for such assembly and disassembly.

A more detailed and important object resides in the provision of an arrangement whereby the connecting bars of the rigid frame members may be carried thereby, to lie substantially in the planes of such members in the knockdown condition of the crate.

A further object resides in the provision of an improved latch structure for connecting the various portions of the knockdown crate, which structure also serves to materially strengthen the crate.

With the above and other objects and advantages in view, the invention resides more particularly in the novel combination, formation and arrangement of parts herein-after described and particularly pointed out in the appended claims.

In the accompanying drawings:

Figure 1 is a perspective view of the improved crate in assembled condition.

Fig. 2 is an elevational view of the assembled crate.

Fig. 3 is an elevational view of one of the latch connections, with the casing plate removed.

Fig. 4 is a sectional view on the line 4—4 of Fig. 3.

Fig. 5 is an elevational view of one of the pivoted connections of the connecting bars, with the casing plate removed.

Fig. 6 is a perspective view of one of the connecting bars.

Fig. 7 is a detail perspective view showing the mounting of a corner plate.

Referring now more particularly to the accompanying drawings, the improved knockdown crate comprises a pair of rigid rectangular frame members which are releasably held in spaced relation forming the 65 crate by a plurality of connecting bars, such release of the connecting bars permitting mutual disconnection of the frame members and permitting the connecting bars to swing into the planes of the frame members to 70 which they are attached whereby in the disassembly of the crate, said crate may occupy a space equal to the combined transverse widths of the frame members.

Each of the frame members comprises side 75 and end bars 10 and 11 respectively which are preferably formed of wood and are secured together in rectangular relation, with the edge portions of the bars lying in parallel planes, and these frame bars 10 and 80 11 are connected by side and intermediate bars 12 and 13 and a diagonal bar 14. Bars 12 and 14 are secured to those edge portions of the bars 10 and 11 that are disposed outwardly in the assembled condition of the 85 crate structure, and bars 13, which are of less thickness than the widths of bars 10, are set flush with said edge portions. Thus there is afforded what may be termed rigid side portions having inturned marginal 90 walls formed by the first named frame bars 10 and 11.

For detachably connecting these rigid side portions, a corner plate 15 is secured to the outer face of each end of each of the frame 95 bars 12 and has wings 16 and 16' disposed respectively over the end face portions of the bars 10 and 11. An angle casing plate has its end portions 17 and 17^a in turn disposed over the wings 16 and 16' respectively, 100 and is held in spaced relation thereto by spacer members 18 and 18^a, the plates, wings, and spacer members being secured together and to the frame bars by screws 19 passed therethrough into the frame bars. The 105 structure thus described affords an efficient reinforcement for the corners of the rigid side portions of the crate. Pivottally secured between the end portion 17 of each angle plate and the adjacent wing 16, by means 110 of a rivet 20 is one end of a connecting bar 21 which is preferably formed of strap metal

and which has its other end engageable between like elements at the corresponding corner of the other rigid crate side member, and provided with a transverse slot 22 open 5 at one side and adapted to receive a locking pin 23 extending through said elements. For locking the bar in this assembled position, a pair of spacer members 18^a are associated with the casing plate end 17^a and 10 disposed at the outer side thereof. The members 18^a are spaced to afford a transverse passageway and slidably mounted in this passageway is a latch bolt which has a head portion 25 at its inner end engageable 15 in a keeper recess 26 in the end of the bar 21. The other end of the latch bar is enlarged and apertured to form a retracting eye 27 which is engageable to retract the bolt and 20 normally stands in mating cut-outs 28 in the adjacent edges of the members 18^a. Said latch bolt is resiliently urged to latched position by an expansive spring 29 disposed in a recess 30 of one of the spacer members, the head 25 of the bolt being beveled to provide 25 for automatic engagement with the bar 21 upon its movement to latching position, and the bolt being limited in its movement under influence of the spring by abutment of the eye 27 with the inner walls of the cut-outs 28 30 into which it is movable.

By the foregoing construction it will be seen that each pair of adjacent corners of the rigid side members has associated therewith a pair of connecting bars 21, which 35 when in assembled position are disposed in right angular relation, each one of the bars being in permanent pivotal connection with one of the side members whereby it may swing to lie along the corresponding wall 40 portions of the side member, which may be either one of the frame bars 10 or 11. Pivotal movement of each bar 21 to collapsed position is limited by abutment with the corresponding spacer member 18, and it is 45 noted that one edge of the pivoted end of each bar 21 is shouldered at 21' to abut against said spacer member.

A further connecting means for the rigid crate sides is afforded by diagonal connecting bars 31 each of which is pivotally secured 50 to one of the frame bars 11 of one rigid side of the crate and adapted for latch connection with the corresponding frame bar of the other rigid side of the crate, the pivot 55 and latch connections being similar to the connections of the bars 21. The pivotal connection for each bar 31 comprises inner and outer plates 32 and 33 secured to the frame bar 11 and spaced by a member 34, 60 said plates mounting a pivot bolt 35 for the end of the bar 31. The latch end of the bar is engageable between the inner and outer spaced plates 30 and 31 on the opposite frame bar 12, said plates mounting a locking pin 38 similar to the pin 23 and having 65

movable therebetween a latch bolt 39. In its collapsed position, the bar 31 lies along the outer face of the frame bar 10, to which it is secured at one end, and by the diagonal extension of the bars 31, the crate structure 70 is sufficiently braced against collapsing movement under normal stresses.

The entire crate structure may be most readily set up or disassembled, and it will be observed that various changes and modifications of structure to meet differing conditions of use and to adapt the device for different articles to be shipped, may be employed, without departing in any manner from the spirit of the invention as interpreted in the accompanying claims.

What is claimed is:

1. A knockdown crate including a pair of side frame portions, base plates secured to each side frame and having lateral extensions embracing the adjacent frame portion, angular casing plates secured outwardly of and spaced from said extensions, connecting bars each having one end pivotally secured between a casing plate and a base plate extension and having its other end engageable between a casing plate and base plate extension of the other side frame and latch means for holding said other end of the bar in such position.

2. A knockdown crate including a pair of rectangular side frame portions, a base plate secured to each corner of each frame and having lateral extensions embracing the adjacent frame portion, an angular casing plate secured outwardly of and spaced from said extensions, connecting bars each having one end pivotally secured between a casing plate and base plate extension and having its other end engageable between a casing plate and base plate extension of the other side frame and latch means for holding said other end of the bar in such position.

3. A knockdown crate including a pair of rectangular side frame portions, a base plate secured to each corner of each frame and having lateral extensions embracing the adjacent frame portion, an angular casing plate secured outwardly of and spaced from said extensions, connecting bars each having one end pivotally secured between a casing plate and base plate extension and having its other end engageable between a casing plate and base plate extension of the other side frame the outer end of each bar being provided with a keeper recess and a latch bolt slidable between the corresponding base plate extension and casing plate for engagement in said recess.

In testimony whereof I affix my signature 125 in the presence of two witnesses.

CHARLES LOMBARDO.
